INCLINOMETER

Thomas Scott Rigby, Coconut Grove, Fla.

Application September 14, 1936, Serial No. 100,721

3 Claims. (Cl. 33—215)

The present invention relates to new and useful improvements in inclinometers for aeroplanes and has for its primary object to provide, in a manner as hereinafter set forth, an instrument 5 of this character embodying a novel construction, combination and arrangement of parts through the medium of which the pitch, bank or side slip of a plane will be immediately and accurately indicated.

10 Other objects of the invention are to provide an inclinometer of the aforementioned character which will be comparatively simple in construction, strong, durable, highly efficient and reliable in use, compact and which may be manufactured at low cost.

15 All of the foregoing and still further objects and advantages of the invention will become apparent from a study of the following specification, taken in connection with the accompanying drawings wherein like characters of reference 20 designate corresponding parts throughout the several views, and wherein:—

Figure 1 is a view in front elevation of an inclinometer constructed in accordance with the 25 present invention.

Figure 2 is a vertical sectional view, taken substantially on the line 2—2 of Figure 1.

Figure 3 is a top plan view of the invention.

Figure 4 is a view in transverse section, taken 30 substantially on the line 4—4 of Figure 2.

Figure 5 is a detail view in horizontal section, taken substantially on the line 5—5 of Figure 4.

Referring now to the drawings in detail, it 35 will be seen that the embodiment of the invention which has been illustrated comprises a circular metallic plate 1 which is adapted to be secured on an instrument board or panel 2 over an opening 3. On the front of the circular plate 1 is a recessed dial 4 and said plate is further 40 provided with a vertical slot 5. It will be observed that the dial 4 comprises a comparatively long intermediate horizontal bar 6 (see Figure 1) representing the horizon and above and below which are comparatively short horizontal bars 7.

45 The vertical slot 5 passes through the bars or markings 6 and 7.

Projecting from the back of the plate 1 are lugs 8 between which a pair of spaced, parallel, vertical rods 9 extend. Slidably mounted on the 50 rods 9 is an indicator carriage 10 having journaled therein a shaft 11 which projects through the slot 5 and has fixed on its forward end a horizontal indicator 12 representing the wing of the plane. Depending from the other end of the 55 shaft 11 is an apertured lever 13.

Also mounted on the back of the plate 1 and projecting horizontally therefrom is a substantially U-shaped bracket 14 having outturned end portions secured to said plate 1, as at 15. Journaled for rocking movement in the outer portion of the bracket 14 is a block 16 having a slot 17 therein. Traversing the slot 17 is a pin 18 (see Figure 2) on which the stem 19 of a pendulum 20 is journaled. It will thus be seen that the pendulum 20 is mounted for universal swinging movement in the bracket 14. Fixed in the upper end of the pendulum stem 19 and projecting forwardly therefrom is a finger 21 having its free end portion loosely engaged in the aperture which is provided therefor in the lever 13.

5 10 15 It is thought that the operation of the instrument will be readily apparent from a consideration of the foregoing. When the plane is traveling on an even keel the indicator 12 parallels the comparatively long intermediate bar 6 which, as hereinbefore stated, represents the horizon, as best seen in Figure 1 of the drawings. However, should the plane dip the pendulum 20 will immediately cause the indicator 12 to move downwardly from the horizon 6 in a manner to apprise the pilot of the condition. Should the nose of the ship rise, the pendulum 20 immediately swings rearwardly for elevating the marker 12.

20 25 30 35 Should the plane bank the pendulum 20 swings laterally toward the low side, thus moving the finger 21 laterally in a manner to actuate the lever 13, rock the shaft 11 in the slideable carriage 10 and, of course, rock the indicator 12. As also hereinbefore stated, the indicator 12 represents the wing of the plane. By comparing the indicator 12 with the bars 6 and 7 the degree of bank may be readily ascertained. A skid may be readily detected due to the fact that the pendulum will swing outward in the direction of the skid.

40 45 50 It is believed that the many advantages of an inclinometer constructed in accordance with the present invention will be readily understood, and although a preferred embodiment of the instrument is as illustrated and described, it is to be understood that changes in the details of construction and in the combination and arrangement of parts may be resorted to which will fall within the scope of the invention as claimed.

What is claimed is:—

55 55 55 1. An inclinometer comprising a plate including a dial, said plate having a vertical slot therein, rods mounted on the plate, a carriage slideable on said rods, a shaft journaled in the carriage and operable in the slot, an indicator fixed on

one end of the shaft and cooperable with the dial, a lever on the other end of said shaft, and gravity actuated means operatively connected to said lever for rocking the shaft in the carriage and for shifting said shaft in the slot.

5 2. An inclinometer comprising a plate including a dial, said plate having a vertical slot therein, a carriage slidably mounted on the plate, a shaft journaled in said carriage and operable in the slot, an indicator fixed on one end of the shaft and cooperable with the dial, a lever on the other end of said shaft, said lever having an opening therein, a bracket mounted on the plate, a pendulum mounted for universal swinging movement 10 on said bracket, and a finger mounted on the pivoted end of the pendulum and engaged in the opening in the lever for rocking, raising and lowering the shaft.

15 3. An inclinometer comprising a circular plate

including a dial on one side, said plate having a vertical slot therein, lugs projecting from the other side of the plate, a pair of spaced, parallel rods extending vertically between the lugs, a carriage slidably mounted on said rods, a shaft journaled in said carriage, said shaft being operable in the slot, an indicator fixed on one end of the shaft and cooperable with the dial, a lever on the other end of the shaft, said lever having an opening therein, a substantially U-shaped bracket mounted horizontally on said other side of the plate, a block rockably mounted in said bracket, said block having a slot therein, a pendulum pivotally mounted in the second-named slot, and a finger mounted on the pivoted end of the pendulum and engaged in the opening in the lever for raising and lowering the carriage and for rocking the shaft in said carriage.

5 10 15 THOMAS SCOTT RIGBY.
